UNITED STATES PATENT OFFICE.

THOMAS F. HATHAWAY, OF ELGIN, ILLINOIS, ASSIGNOR TO ILLINOIS WATCH CASE COMPANY, OF ELGIN, ILLINOIS, A CORPORATION OF ILLINOIS.

CIGARETTE-CASE.

1,256,555.

Specification of Letters Patent. Patented Feb. 19, 1918.

Application filed April 6, 1916. Serial No. 89,320.

To all whom it may concern:

Be it known that I, THOMAS F. HATHAWAY, a citizen of the United States, residing at Elgin, county of Kane, and State of Illinois, have invented certain new and useful Improvements in Cigarette-Cases, of which the following is a specification.

The present invention has to do with cigarette cases and the like. The main object 10 of the invention is to provide an article of this kind, having in one of its walls a secret compartment of construction suitable to accommodate one or more pictures such as photographs and the like. It is desired in 15 this connection to provide a construction such that the wall, wherein said secret compartment is formed, shall look to all intents and purposes like an ordinary wall, so that the presence of the secret compartment will not 20 be revealed, except upon careful examination of the article. It is furthermore desired in this connection to so form the parts that said secret compartment may be provided with a minimum amount of encroachment upon the 25 space within the body of the case, and also without making the case undesirably thick or bulky.

Still another object of the invention is to provide a very simple form of construction 30 and one which may be cheaply manufactured from a minimum number of parts and assembled with a minimum amount of labor.

Other objects and uses of the invention will appear from a detailed description of 35 the same, which consists in the features of construction and combinations of parts hereinafter described and claimed.

Referring to the drawings:

Figure 1 shows a perspective view of the 40 interior of the cigarette case, the secret compartment being opened so as to expose the interior construction of the same; and

Fig. 2 shows a cross-section through the cigarette case, the secret compartment being 45 closed.

Reference to the figures shows that the case is built up from the leaves 3 and 4, which may be of the usual or familiar type of construction. It is customary in the manufacture of articles of this kind to provide each 50 of the leaves with an inturned peripheral flange 5, so that when the case is closed the flanges on the two leaves will come together and form a solid or firm contact with each other. A catch 6 of the usual type is pro-

vided for locking the two leaves together when the case is closed.

The two leaves are hinged together by a pin 7 which extends through the coöperating lugs 8 and 9 on the leaves 3 and 4 respectively. A tongue 10 of the usual form may be provided for holding the cigarettes in position against the leaf 3 in the manner which is well understood in the art. This tongue is also hinged on the pin 7 by means of the lug 11.

A false leaf 12 is provided for the secret compartment 4, said false leaf being of thin material and of size and contour to seat down snugly within the peripheral flange 5 of said leaf 4. For this purpose the false leaf is conveniently provided with an upstanding peripheral flange 13 of a size to seat nicely within the flange 5, the edge of the flange 13 registering substantially with the surface of the flange 5. By the use of this construction, when the cigarette case is opened with the false leaf 12 lying in position within the leaf 4, the appearance of the article to the observer is substantially that of an ordinary cigarette case. Each leaf presents the appearance of having a depressed central portion, and the depressions of the two portions coöperate to provide the space wherein the cigarettes are supported. Furthermore, it is 85 customary to offset the tongue 10 substantially as shown at the point 14 in Fig. 1, so as to give an increased clearance for the accommodation of the cigarettes between the tongue and the leaf 3. By depressing the 90 central portion of the false leaf 12, a space is provided for the reception of the tongue, taking into account the fact that the tongue throughout the major portion of its length lies to one side of the pivotal pin.

The false leaf is conveniently pivoted on the same pin 7 as joins together the leaves 3 and 4 and the tongue 10. For this purpose the false leaf is provided with one or more lugs 14 through which the pin 7 passes.

In order to retain the false leaf locked normally in position against and within the leaf 4, I have illustrated the catch 15 on the false leaf. Said catch is shown as comprising an elongated body portion 16, having the undercut head portion 17. The body portion 16 is adapted to seat into a recess 18 formed in the flange 5 of the leaf 4, and the undercut head portion 17 is adapted to lock against the edge of said recess 18. By this 110

arrangement, when the false leaf is locked in the closed position, the catch 15 merges in appearance with the body portion of the leaf 4, so that its presence does not become apparent except upon careful examination of the article.

On the inner face of the false leaf any suitable receptacle may be provided for the accommodation of one or more pictures or the like. In the construction illustrated I have shown a plate 19 having its edges and bottom portion inturned and secured to the back face of the false leaf, so as to leave a slight clearance between the plate 19 and the false leaf. Into this clearance may be inserted one or more pictures which will be observable through the openings 20 of the plate. I prefer to flange the lower and side edges of the plate 19 but to leave its upper edge unflanged, so that the openings through which the pictures are inserted or withdrawn are adjacent to the same edge to which the catch 15 is secured upon the false leaf. Ordinarily when the secret compartment is to be opened, the catch 15 will be at the top of the article and therefore by using the arrangement just described the openings for the insertion and withdrawal of the pictures will also be brought to the top side of the compartment.

While I have herein shown and described only a single embodiment of my invention, still it will be understood that I am in no wise limited to said embodiment, except as

35 I may limit myself in the claims.

I claim:

1. In a device of the class described, the combination, of a pair of leaves, each leaf having its central portion depressed and being provided with a peripheral inturned flange, coöperating lugs on the leaves, a pin extended through said lugs and serving to hinge them together, a false leaf hinged on said pin, said false leaf having its central portion depressed and being provided with a peripheral flange of size and contour to seat within the flange of one of the leaves, the flange of said leaf alining with the flange of the leaf into which it seats when it is to be seated, a receptacle for a picture or the like on the back false leaf, and means for locking the false leaf to the leaf into which it seats, for the purpose specified.

2. In a device of the class described, the combination, of a pair of leaves, coöperat-

ing lugs on said leaves, a pin extended through all of said lugs and serving to hinge the leaves together, the central portion of each leaf being depressed, a peripheral flange on each leaf, said flanges seating 60 squarely together when the leaves are folded together, a false leaf hinged on said pin, a peripheral flange on the false leaf adapted to seat into and register with the peripheral flange of one of the first mentioned leaves, the central portion of the false leaf being depressed, means for locking the false leaf to the leaf into which it seats, and a tongue hinged on said pin, said tongue being of formation suitable to seat into the depressed portion of the false leaf, for the purpose specified.

3. In a device of the class described, the combination, of a pair of leaves, a pin on which said leaves are hinged, one of said leaves being of pan-shaped formation, a false leaf hinged on said pin, said false leaf being of pan-shaped formation and adapted to seat evenly into the first mentioned pan-shaped leaf, a receptacle for a photograph or the like on the back face of the false leaf, and means for locking the false leaf to the leaf into which it seats, for the purpose specified.

4. In a device of the class described, the combination of a pair of leaves, a pin on which said leaves are hinged, a false leaf hinged on said pin, said false leaf being of contour appropriate to seat evenly into one of the first mentioned leaves, a receptacle 90 for a photograph or the like on the back face of said false leaf, and means for locking the false leaf to the leaf into which it seats, for the purpose specified.

5. A case having, in combination, a front 95 cover, a back cover, an intermediate cover with its edges closely fitting into one of said other covers, and a pintle upon which said three covers are pivoted.

6. A casing having, in combination, a front cover, a back cover, an intermediate cover with its edges closely fitting into one of said other covers, and with a space between the adjacent faces of said two last-named covers, and a pintle upon which said three covers are pivoted.

THOMAS F. HATHAWAY.
